UNITED STATES PATENT OFFICE.

DAVID T. WILLIAMS, OF PATERSON, NEW JERSEY, ASSIGNOR TO STANDARD STOKER CO. INC., OF WILMINGTON, DELAWARE, A CORPORATION OF DELAWARE.

CONVEYER.

1,099,956.

Specification of Letters Patent. Patented June 16, 1914.

Application filed June 10, 1913. Serial No. 772,760.

To all whom it may concern:

Be it known that I, DAVID T. WILLIAMS, a subject of the King of England, residing at Paterson, in the county of Passaic and 5 State of New Jersey, have invented certain new and useful Improvements in Conveyers, of which the following is a specification.

This invention relates to conveying means, for instance, such as are employed in mechanical stoker equipment in conjunction with a locomotive and its tender, of the class in which with a suitable passaged structure there is operatively combined a rotating screw for advancing the material, such as 10 coal, through said structure. In these constructions it is desirable that the means for imparting rotary motion to the screw shall be so constructed and so related to the screw as not to impair its efficiency, as by in any 15 way interfering with the progress of the material being advanced. According to the present invention, therefore, the screw has coaxial and rotating with it a driven gear member which is annular in form and other- 20 wise adapted to allow unimpeded progress of the material therethrough, and in order to prevent particles of the material being advanced from having access to the driving tread of said gear member or in any other 25 way getting between it and the driving gear member, with the consequence of wearing or injuring them or clogging their action, said driven gear member has its driving tread in a novel manner housed in the ad- 30 joining ends of sections of said structure and sealed off from the passage thereof. Fur- 35 thermore, a part of the screw has an increased pitch for purposes appertaining to the uniform advance of the material through 40 said structure.

In the accompanying drawings, in which, simply by way of example, I have illustrated my invention in connection with the conveying means of a mechanical stoker equipment 45 between a locomotive and its tender, Figure 1 is a longitudinal sectional view of such conveying means constructed in accordance with the present invention; Fig. 2 shows its trough *a* and a driving gear member in ele- 50 vation, looking toward the left in Fig. 1, the other moving parts being omitted; Fig. 3 shows the trough section *a'*, the screw *k* and driven gear member in end elevation, looking toward the left in Fig. 1; Fig. 4 is

a vertical sectional view of the bowl-end portion of the trough *a*; Figs. 5 and 6 are sectional views of the element including a part of the screw and the driven gear member; Fig. 7 is a sectional detail view illustrating the seal-forming means; and, Fig. 8 is a 55 fragmentary elevation of the sealing ring.

The troughs *a* and *b* shown in Fig. 1 are suitably formed and fitted together at *c* to produce a bowl-shaped universal joint permitting the structure to accommodate itself 60 to relative movement as between the locomotive and its tender, in accordance with the usual construction. The trough *a* is divided into two sections, *a'*, *a''*, whose adjoining ends are suitably interlocked with each other 65 by an annular telescoped joint *d* and provided with external flanges *e*, bolted together. Together these sections form between them a cross-sectionally T-shaped continuous groove *e'*, and each has also an annular groove *f* opening toward the other section, the two grooves *f* being opposite. The section *a'* is provided with a top wall, 70 part of which may be integral therewith and part removable, as shown in Fig. 1, to allow 75 access to the interior of the trough, and it has depending from the integral part of its top wall a suitable bearing bracket *g*. At the top and on the inside of sections *a''*, which is generally part-spherical in form 80 and open at the top, are the opposite 85 grooved supports *h* receiving the tongued portions of a bearing bracket *i* depending therefrom.

In the brackets *g* and *i* is journaled the 90 shaft or axis portion of a spiral feed screw *k*, the major part of whose blade appears integral with the shaft or axis as herein illustrated. The remaining portion of the blade, designated *k'* in the drawings, is a 95 separable part thereof formed around a hub *l* which is splined on the shaft and, together with a single screw-blade-shaped spoke *m*, carries an annular peripherally toothed driven gear member *n* whose interior diameter is at least as great as that of the trough. As shown, the hub, spoke *m*, part *k'* of the screw and member *n* are integral in the present instance. In cross-section, Figs. 5 to 7, the perimeter-portion of 100 this gear is T-shaped, and it is housed within the T-shaped groove *e'* of the sections *a'*, *a''*. As illustrated, shaft *j* has a suitable

universal joint connection *o* with the shaft of another feed screw *p* which advances the coal to the screw *k* in the usual way.

The sections *a'* *a''* are formed with an opening *q* entering from the exterior into the groove *e'* and thus exposing a limited portion of the toothed periphery of gear member *n*; this opening is at the under side of trough *a* in the present instance, and it receives a driving gear member *r*, which meshes with gear member *n* and may be driven in any manner (not shown). Thus, the power being transmitted to the screw through an annular gear member *n* which is coaxial and rotative therewith and receives the driving force exteriorly of the passage of the trough and which is further so formed and related to said passage as not to impede the progress of the coal or interfere with the advancing influence of the screw thereon—the surface thereof exposed to the coal being relatively limited and therefore having substantially negligible influence itself to rotate or turn the body of coal—a considerable increase in efficiency over known constructions is obtained. The part *k'* of the screw has a somewhat greater pitch than the remainder so as to give as much freeway between the convolutions of the screw blade as would exist if the spoke *m* were not present and to compensate for any tendency toward retardation in the advance of the coal due principally to an interruption in the propelling means being produced where the coupling *o* occurs.

The sealing off of the driving tread of the gear member *n* from the passage of the trough, whereby to prevent particles of coal or the like from being caught between the driving and driven members *r* and *n*, may be accomplished by the following means: Rings *s* are fitted in the grooves *f*, bearing against the opposite faces of the gear *n* and preferably seating in shallow grooves *t* therein, being held in contact with the gear by the system of springs *u* housed in the rings and held against rotation by the studs *v* entering notches *w* (Fig. 8) in the grooves *f*.

I do not wish to be limited to the precise construction shown and described herein, what I claim being:

1. The combination of an advancing means including a rotary screw and an open

driven gear member coaxial therewith, a 55 passaged structure housing the rotary structure and including two sections meeting end to end, and a driving gear member arranged exteriorly of the passaged structure and having peripheral driving contact with the 60 driven gear member, the adjoining ends of said sections housing approximately all of the periphery of the driven gear member excepting that receiving the contact of the driving gear member, substantially as described. 65

2. The combination of an advancing means including a rotary screw and an open driven gear member coaxial therewith, a 70 passaged structure housing the rotary structure and including two sections meeting end to end, a driving gear member arranged exteriorly of the passaged structure and having peripheral driving contact with the driven gear member, the adjoining ends 75 of said sections housing approximately all of the periphery of the driven gear member excepting that receiving the contact of the driving gear member, and means to seal off the periphery of said driven gear member 80 from the passage of the passaged structure, substantially as described.

3. In combination, with a passaged structure, means to advance the material there-through including a rotary screw having its 85 axis extending longitudinally of the passage of said structure and an open driven gear member surrounding said screw and having an inwardly projecting spoke, said screw having an increased pitch where it penetrates said member, substantially as described. 90

4. In combination, with a passaged structure, means to advance the material there-through including a rotary screw having its 95 axis extending longitudinally of the passage of said structure and including two spaced screw portions, the end of one screw portion which adjoins the space between said screw portions having a relatively increased pitch, 100 substantially as described.

In testimony whereof I affix my signature in presence of two witnesses.

DAVID T. WILLIAMS.
